FIG. 1 is an isometric view of the top, front and one side of a hospital showing my new design;

FIG. 2 is an isometric view of the top, rear and the other side thereof;

FIG. 3 is a fragmentary transverse sectional elevational view looking forwardly through the domed solarium and at the front gable; and

FIG. 4 is a fragmentary side elevational view showing roof contour, the roof contour for the other side appearing in opposite correspondence.

The right inside rear wall in FIG. 2 is the same as the left inside wall except the provision of a conventional door and steps.

I claim:

The ornamental design for a hospital, as shown and described.
